UNITED STATES PATENT OFFICE

FRIEDRICH TEMLER, OF COLOGNE-NIPPLES, GERMANY

ARCH SUPPORT FOR SHOES

Application filed April 24, 1929, Serial No. 357,663, and in Germany November 8, 1928.

The object of this invention is to provide an arch support for boots and shoes, which can very readily be renewed or changed when required, but is nevertheless held securely in position, when in use, so that it is not liable to shift and become uncomfortable.

To this end I use a substantially flat retaining spring, attached to the shoe sole and having a socket at each end, and an arched foot supporting spring, the ends of which engage into the said sockets, but can readily be removed therefrom when required. The retaining spring may be attached to the under side of the insole, the latter, however, having openings for the sockets, so that the sockets are accessible from top. The ends of the arched foot supporting spring can only enter the sockets to a limited extent, so that the spring is maintained, under pressure, in its arched state, even if made comparatively light and easily flexible.

An arch support according to the invention is shown in the accompanying drawings, in which

Fig. 1 is a plan view of the insole, without the foot supporting spring.

Fig. 2 is a perspective view of the retaining spring, and

Fig. 3 is a side view thereof.

Fig. 4 is a plan view of the insole with the foot supporting spring in position, indicating also by a broken line the outline of a leather or like pad which may be attached to the foot supporting spring.

Fig. 5 is a plan view of the foot supporting spring, and

Fig. 6 is a side view thereof.

In the drawings *a* represents the insole and *e* the substantially flat retaining spring, which has rivet holes *b* for attaching it to the underside of the insole by means of rivets *b*¹. The spring *e* has at its ends sockets *d* and *c*, and the insole has openings *a*¹, corresponding in shape to the outlines of the sockets, whereby the sockets are rendered accessible from

the top. The socket *c* is formed by bending over two lateral flanges *c*¹ of a plate in which the spring terminates, and there is a gap between the edges of these flanges, so that the socket is open at the top.

The arched foot supporting spring, designated *f* in the drawing, has attached thereto, by rivets *l*, a leather pad *h*, only the outline of which is indicated by a broken line in Fig. 4. The front end *i* of the spring *f* is tapered, so that it can enter the socket *d* to a limited extent. At the rear the spring *f* terminates in a lug *m* narrower than the gap between the flanges *c*¹. This lug carries, by means of a rotatable, notched stud *g*, a short, flat bar *h*, which can be set parallel with the lug, to pass through the slot into the socket, and can then be rotated to engage under the edges of the flanges *c*¹, whereby the lifting of the spring *f* is prevented. The two shoulders *f*¹ of the spring *f*, at the inner end of the lug *m*, are unable to enter the socket *c*, and thus limit the extent to which the spring *f* can be extended by the pressure of the foot.

For applying the arched spring *f* to the shoe the tapered end *i* of the spring is first inserted into the socket *d*, and then the lug *m* is dropped into the socket *c*, the bar *h* being for this purpose placed parallel with the lug, but being subsequently rotated into the position shown in Figs. 4 and 5, to engage the spring with the socket.

What I claim as my invention and desire to secure by Letters Patent of the United States is:—

1. In an arch support for shoes the combination of a substantially flat retaining spring, two sockets fixed to said spring, one at each end thereof, one of said sockets having a slot at the top, an arched foot supporting spring having at one end thereof a lug adapted to enter the slotted socket by passing through said slot, the other end being adapted to engage into the other socket, and

a bar fulcrumed on said lug, adapted to engage under the edges of said slot.

2. The combination, with the insole of a shoe, of a substantially flat retaining spring fixed to the under side of said insole, two sockets fixed to said spring, one at each end thereof, said insole having apertures whereby said sockets are accessible from the top, and an arched foot supporting spring having end portions adapted for engagement with said sockets.

3. In an arch support for shoes the combination of a substantially flat retaining spring, two sockets fixed to said spring, one at each end thereof, one of said sockets having a slot at the top, an arched foot supporting spring having at one end thereof a lug adapted to enter the slotted socket by passing through said slot, the other end being tapered and adapted to engage into the other socket, and a bar pivoted to said lug, adapted to engage under the edges of said slot.

4. In an arch support for shoes, the combination of an insole having openings therein, a substantially flat retaining spring fastened to the underside of the insole and having a socket at each end thereof exposed through said opening in the insole, and an arched foot supporting spring arranged upon the upper side of the insole and having end portions engaging said sockets of the retaining spring.

5. In an arch support for shoes, the combination of an insole having openings therein, a substantially flat retaining spring fastened to the underside of the insole and having a socket at each end thereof exposed through said openings in the insole, one of said sockets having an entrance at its inner end and the other socket having an entrance slot in its top, an arched foot supporting spring arranged upon the upper side of the insole and having an end portion longitudinally insertible into and withdrawable from the first-named socket through the end entrance thereof and having an opposite end portion insertible into and withdrawable from the second-named socket and through the top slot thereof, and a fastening member carried by the latter-named end of the arched spring for movement into and out of engagement with the walls of said socket to retain said end of the arched spring therein.

6. In an arch support for shoes, the combination of an insole, a substantially flat retaining spring arranged upon the underside of the insole and having a socket at each end thereof, the insole being provided with openings rendering said sockets accessible from above, an arched foot supporting spring arranged upon the upper side of the insole and having end portions engaging with said sockets of the retaining spring, and a foot pad on said arched spring.

7. In an arch support for shoes, an insole,

a substantially flat longitudinally disposed retaining spring on the underside of the insole, the latter having openings therein exposing the ends of said spring, and an arched foot supporting spring on the upper side of the insole having end portions detachably interlocked with the exposed end portions of the retaining spring.

In witness whereof I have signed this specification.

FRIEDRICH TEMLER.
